Specification for Design.

Patented Nov. 19, 1907.

Application filed May 4, 1907. Serial No. 371,935. Term of patent 7 years.

To all whom it may concern:

Be it known that we, LIONEL STRASSBURGER, a citizen of the United States, and CHARLES NELSON, a subject of the King of Sweden, both residing in the borough of Brooklyn, county of Kings, and State of New York, have invented a new, original, and ornamental Design for a Chafing-Dish, Stand and Lamp, of which the following is a specification, reference being had to the accompanying drawing, forming part thereof.

The figure is a perspective view of a chafing dish, stand and lamp showing our new design.

We claim:

The ornamental design for a chafing dish, stand and lamp, as shown.

LIONEL STRASSBURGER.
CHARLES NELSON.
